US0D1000116S

(12) **United States Design Patent** (10) **Patent No.:** **US D1,000,116 S**
(45) **Date of Patent:** ** *Oct. 3, 2023

(54) **DEVICE STORAGE CASE**

(71) Applicant: **META PLATFORMS TECHNOLOGIES, LLC**, Menlo Park, CA (US)

(72) Inventors: **David Michael Pickett**, Seattle, WA (US); **Shane Michael Ellis**, Bellevue, WA (US)

(73) Assignee: **Meta Platforms Technologies, LLC**, Menlo Park, CA (US)

(*) Notice: This patent is subject to a terminal disclaimer.

(**) Term: **15 Years**

(21) Appl. No.: **29/747,261**

(22) Filed: **Aug. 20, 2020**

(51) LOC (14) Cl. **03-01**

(52) U.S. Cl. **D3/294**
USPC **D3/294**

(57) **CLAIM**

The ornamental design for a device storage case, as shown and described.

DESCRIPTION

FIG. 1 is a front perspective view of a device storage case showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the device storage case of FIG. 1, shown in an open state;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view thereof, shown in a state of use with additional environment; and,

FIG. 18 is a rear perspective view thereof.

The broken lines showing the additional electronic device in FIGS. 17 and 18 depict environmental subject matter only and form no part of the claimed design; all other broken lines depict portions of the device storage case that form no part of the claimed design.

1 Claim, 14 Drawing Sheets
